UNITED STATES PATENT OFFICE

THOMAS C. SHEEHAN, OF UPPER MONTCLAIR, NEW JERSEY, ASSIGNOR TO DURHAM
DUPLEX RAZOR COMPANY, A CORPORATION OF NEW YORK

BLADE FEED FOR HONING MACHINES

Application filed February 7, 1930. Serial No. 426,477.

This invention relates to an improvement in blade feeds for honing machines and the like, particularly those used in the manufacture of slotted safety razor blades. In such machines a stack of the blades is commonly supported on an arbor extending through the slot in the blades, and these blades are taken from the stack one by one by lugs on a moving blade forwarding device adjacent the foremost blade in the stack. An example of a blade feed of the type that the present invention is designed to improve is shown in Patent No. 1,166,012 to T. C. Sheehan, dated December 28, 1915, particularly in Figs. 5 and 6.

Trouble has resulted in such devices through binding or hanging up of the blades on the arbor due apparently to friction between the arbor and the slot surface of the blades when the blade skews or tilts out of perpendicular to the arbor. As a result the blade is not pushed fully forward against the forwarding device but is held back a little, permitting the rapidly traveling lugs on the forwarding device to strike the inclined face 25 of the blade beyond the end of the slot. This breaks the blade and results in serious losses.

It has been discovered that the above difficulty can be avoided in the type of blade which has salients extending into the slot by 30 providing channel sections in the feed arbor in which the salients ride so that the blades are supported at several points of contact by the salients and the blade is otherwise free from engagement with the arbor.

It is therefore the main object of the present invention to provide a better blade feed, relatively free from the above defect, carrying this discovery into effect. With this and other objects in view the invention consists 40 in certain constructions and combinations hereinafter fully described and then particularly pointed out in the appended claim.

In the accompanying drawings in which like characters of reference indicate the same or like parts, Fig. 1 is a plan view partly broken away of a blade feed constructed in accordance with the invention; Fig. 2 is a side elevation partly in section on the line 2-2 of Fig. 1.

In carrying the invention into effect, there

is provided in a blade feed for honing machines, a blade supporting arbor having oppositely disposed blade engaging sections adjacent its sides, and a blade having section engaging salients and otherwise free from engagement with said arbor in order to provide a relatively frictionless contact between the blade and arbor. In the best constructions, such sections include channels, and said salients have channel engaging knife edges.

Referring now to the drawings, the blades 5 to be fed, Fig. 2, are provided with slots 6 for admitting the studs or rib by which the blades are positioned in a holder for use in shaving. The blades illustrated are adapted for use either in the well known type of holder (not shown) which has a plurality of spaced studs with each two oppositely disposed pairs of salients 7 engaging the studs in the same way that they engage the lugs 11 in the device disclosed, or may be used in another well known type of holder having an axial rib, the tips of the opposed salients being spaced apart the width of the rib.

The arbor 8 on which the blades are slideable toward the feed belt 10 is provided with tapered channels 9 having rounded or concave base portions and extending longitudinally of the arbor. The salients 7 are of triangular shape with the points or short knife edges thereof resting on the concave base of the channels when the blades are stacked on the arbor. The arbor is a flat bar of generally rectangular shape somewhat smaller in cross section than the slot so that the blade engages the channel sections only of the arbor and is otherwise free from engagement therewith. It will be noted that the engagement between the salients and the channels is like that between the pivot and loop of a weighing balance and consequently that the contacting surface is very small.

Thus the blades will slide smoothly with relatively little friction and without the liability of binding or hanging on the arbor, toward takeoff position. The blades are yieldingly urged toward the belt 10 by any suitable means such as that disclosed in the above noted patent, or by gravity, consequently

after the takeoff of one blade from the stack the next blade will be pushed fully forward to the position shown in Fig. 1 with the front end of the blade against the belt and the rear end of the blade against the stop 12. One of the lugs 11 will then, in the arcuate travel of the belt 10 on the pulley 13, enter the slot and squarely engage the forward end of the slot and carry the blade out between the guides 14 and 15. Owing to the anti-friction point or edge contact of the salients with the arbor grooves the blades will slide easily along the arbor even though the blades have swung somewhat from perpendicular position with respect to the arbor. Hence more perfect feeding and fewer broken blades will result at this critical point in the blade feed.

What is claimed is:

In a blade feed for honing machines, an arbor for supporting slotted razor blades of the type having salients on the slot edge, comprising a bar loosely fitting the slot and having longitudinal grooves for receiving the salients and thereby supporting the blade, said slots being shaped to engage the salients at one point only to provide a relatively frictionless contact between the blade and said bar.

In testimony whereof I have signed my name to this specification.

THOMAS C. SHEEHAN.
